UNITED STATES PATENT OFFICE.

JOHN F. DAILEY, OF ROCHESTER, NEW YORK.

COMBINED GUIDING, GAUGING, AND TIMING DEVICE.

Application filed June 18, 1927. Serial No. 199,845.

A successful playing of golf depends largely on the ability of the player to first place his knees, hips, shoulders, arms and hands in the proper position for his stance and then give his knees, hips, shoulders, arms, and hands, and with them the club, the proper turning and winding movement, first in one direction and then in the other, and timing these movements with relation to each other. The object of my present invention is to provide a simple device that will make the player habitually position his knees and hips, shoulders, arms and hands and the club in the proper manner and time his knee, hip, shoulder, arm and hand movement with relation thereto.

These and other objects of this invention will be fully illustrated in the drawing, described in the specification and pointed out 20 in the claims at the end thereof.

In the accompanying drawing:

Figures 1, 2, 3 and 4 show a player provided with my combined gauge guide and timing device in four successive positions to 25 which his knees, hips, shoulders, arms and hands and club were positioned and guided by the device and the necessary movements brought about and timed with relation to the swinging club.

Figure 5 is a top plan view of the combined gauge, guide and timing device.

Figure 6 is a front elevation of the combined gauge, guide and timing device.

In the several figures of the drawing like 35 reference numerals indicate like parts.

The combined gauge, guide and timing device forming the subject matter of this invention teaches a proper positioning and movement of the knees, hips, shoulders, arms and hands, and the timing of these movements with relation to each other and to the swinging of the club. As illustrated in the figures of the drawing this device comprises a frame formed of suitable material, preferably metal formed into the shape illustrated in the figures. In the frame is provided an open loop or depression 1 which serves to properly gauge and position the arms of the player for addressing the ball and will hereinafter be referred to as the 40 positioning and guiding loop. The frame projects outwardly from the positioning and guiding loop 1 forming a triangular extension with an angular gauging edge 2 provided on one side adjacent to the open end 45 of the positioning and guiding loop 1.

The inner end of the frame is provided with suitable means whereby it can be attached to the belt 6. This, of course, may be done in several ways. In the form illustrated in the figures the inner ends 7 and 8 of the rod stock from which the frame is formed up, are turned down so as to engage into a pair of sockets 9 and 10 provided on the reinforcing strap 11 that is attached to the outside of the belt 6. The reinforcing strap and its sockets can thus be firmly fastened to the body of the player by means of the belt and held in a predetermined position with relation to the body so as to hold 70 the frame on the body of the player in the position illustrated in the figures. The sliding connection of the inner ends 7 and 8 of the frame make it possible to quickly attach or detach the frame from the belt so 75 that it can be used or dispensed with by the player whenever the need arises for the one or the other.

In order to reduce the bulkiness of the frame when detached it may be made in two 80 parts that are joined together by the sleeves 12 and 13. Of these, sleeve 12 is attached to the outer portion of the frame while sleeve 13 is attached to the inner portion of the frame and is larger in diameter than the 85 sleeve 12 so that sleeve 12 can telescope into the sleeve 13 to be supported thereby. The sleeves are preferably oval shaped in cross section so that they cannot turn on each other and hold the parts of the frame in the proper 90 plane at all times.

With the aid of the two telescoping sleeves 12 and 13 the width of the positioning loop may also be increased or decreased to adapt the loop to the particular player who is 95 about to use the device. In order to cushion the wrist or hand, should it come in contact with the frame, a rubber padding 5 is placed around a portion of the frame of the device. This rubber padding may extend from the 100 inside of the positioning and guiding loop 1 to the adjacent angular gauging rail or edge 2 and extend out on the gauging rail or edge to within a short distance from the outer angular extension of the frame.

The belt is placed around the body of the player and the frame attached thereto as illustrated especially in Figure 1 in which the player is placed in the proper initial position for addressing the golf ball. In 110 this position the left arm of the player engages into the open positioning and guiding

loop 1 of the frame and gauges this arm and with it the right arm and the club for the proper position for addressing the ball.

With his eyes on the ball a right handed player then turns and winds his left knee, left hip and left shoulder to the right. This draws his arms gradually out of engagement from the positioning and guiding loop 1 and away from the frame. The turn and wind of the body with left knee, hips and shoulders draws the arms of the player to the right and swings his wrists and club until he has attained the position illustrated in Figure 2. In this position the player is 15 "wound up" and is ready to "unwind" to the left his wound up knee and hips. In "unwinding" the player's knees and hips turns his wound up shoulders with relation to the movement of the knee and hip and together they cause a swinging movement of the shoulders which pull the swinging arms with the assistance of the proper body finish position on the straight left leg swings the wrists and club so that it will direct the 20 club head into and thru the ball with a follow thru. The gauge gauges this stroke by maintaining its position behind the arms in the back stroke thru the proper wind up of the hip and maintains its proper guiding position on the forward stroke by keeping ahead of the arms, wrists and club on the unwinding of the hip. The positioning and guiding loop 1 on the unwind thus gives the direction the arms must follow for the 25 proper follow thru and the correct swing. It also assists in acquiring the proper flail movement of the shoulders and wrists.

The angular gauging edge 2 serves to gauge the correctness of the stroke by providing a visible edge along which the hands must swing at a predetermined distance 30 away from it and parallel thereto.

I claim:

1. In a device of the character described and adapted to be supported by a belt around the body of a player, the combination of frame, a positioning loop in the frame adjacent to the belt and a gauging rail extending outwardly from the open end 45 of said positioning loop.

2. In a device of the character described and adapted to be supported on and fastened rigidly to the body of a golf player, the combination of a frame projecting from the body, a positioning loop formed in one side 50 of said frame, and an angular gauge rail formed one side of said frame adjacent to said positioning loop.

3. A device of the character described comprising a belt, a reinforcing strap attached to said belt, a frame supported by said reinforcing strap, an open loop formed in said frame opposite to said reinforcing strap, and an angular extension projecting from said open loop and forming a gauge 60 rail on one side of said frame.

4. A device of the character described comprising a belt, a reinforcing strap attached to said belt, a brace depending from said reinforcing strap, a frame, means for supporting said frame on said reinforcing strap and hold said frame in a predetermined plane thru said brace in front of the belt, a positioning loop formed in one side 70 of said frame and an angular gauge rail 75 adjacent to said positioning loop and extending the full length of said frame.

5. A device of the character described comprising a belt, means for detachably supporting a frame on said belt, said frame comprising an inner and an outer section, telescoping means carried by each of said inner and said outer section and adapted to telescope over each other to hold said inner section and outer section in line with each 80 other and in a parallel plane to each other, said telescoping means being adapted to increase or decrease the width of said positioning loop.

6. In a device of the character described 90 and adapted to be supported by a belt on the body of a player, the combination of a frame supported by said belt, an outwardly projecting narrow gauging rail formed by said frame and adapted to form an obstruction to the forward movement of the arms in swinging the club in one position of the body and adapted to indicate the direction for the forward movement.

7. In a device of the character described, 100 the combination of an outwardly projecting gauging rail formed by a rod and adapted to be mounted on the body of a player to project outwardly from the body at a predetermined point of the body to form an 105 obstruction to the forward movement of the arms with the body in one position, said gauging rail being adapted to swing sideways on a predetermined movement of the body to permit the arms of the player to 110 swing the club without bringing the arms or any part thereof in contact with the gauging rail.

In testimony whereof I affix my signature.

JOHN F. DAILEY.
